UNITED STATES PATENT OFFICE.

OTTO EICK, OF ST. LOUIS, MISSOURI.

BRUSH FOR BOTTLE-CLEANING MACHINES.

1,199,456.

Specification of Letters Patent. Patented Sept. 26, 1916.

Application filed July 22, 1916. Serial No. 110,786.

To all whom it may concern:

Be it known that I, Otto Eick, a citizen of the United States, residing at St. Louis, in the State of Missouri, have invented a certain new and useful Improvement in Brushes for Bottle-Cleaning Machines, of which the following is a specification.

My present invention pertains to an improvement in brushes for bottle-cleaning machines.

It has for its main object the provision of a brush of such formation as to offer a minimum resistance to the rotation of the brush within the bottle, and to cause the fingers carried at the outer portion of the brush to take a full wiping action against the inner face of the bottle.

The brush is illustrated in the annexed drawing, wherein it is shown in elevation, and may be said to comprise a socketed member 1, from which extend two inclined and divergent arms 2, said arms being preferably connected by an inverted U-shaped member 3. Extending laterally from the outer face of each of said arms and at the upper end thereof is a fin or wiper 4, and preferably at the lower portion thereof I provide two fingers 5 and 6. Intermediate the fin and the upper finger 5 I form a wing 7, having an opening 8 extending therethrough, and projecting outwardly from said wing is a series of fingers 9.

The opening 8 affords a passage through the wing for the water during the rotation of the brush and reduces the resistance of the water against the brush. It likewise produces a better wiping action of the fingers 9 against the wall of the bottle. Furthermore, this construction reduces the bulk of rubber or other material necessary to the

formation of the brush over that which would have to be employed if the wing were made solid. Again, by providing the opening 8, the wing is rendered quite flexible and allows the brush to slip readily through the bottle-neck. In other words, the fingers 9 may project outwardly to a considerable extent beyond the arm 2, and yet they will fold up or bend quite readily as the brush is forced or inserted into the bottle-neck.

Having thus described my invention, what I claim is:

1. A brush for bottle-washing purposes and the like, comprising an arm; and a wing extending laterally therefrom, said wing being provided with an opening extending therethrough from side to side.

2. A bottle-cleaning brush, comprising in combination an arm; a wing extending outwardly therefrom; and a series of fingers carried by and projecting outwardly from said wing, the wing having an opening extending therethrough intermediate the inner ends of the fingers and the supporting arm.

3. A brush for washing bottles, comprising in combination a socketed member; an arm extending outwardly therefrom and at an angle to the axis of the socketed member; a wing projecting outwardly from the outer face of the arm, said wing having an opening extending therethrough from side to side and substantially from the upper to the lower end thereof; and a wiping member extending outwardly from the outer edge of said wing.

In testimony whereof I have signed my name to this specification.

OTTO EICK.
